UNITED STATES PATENT OFFICE.

FRANCIS MARION WISELEY, OF LOS ANGELES, CALIFORNIA.

PUMPING SYSTEM.

1,150,473.

Specification of Letters Patent. Patented Aug. 17, 1915.

Application filed September 2, 1914. Serial No. 859,792.

To all whom it may concern:

Be it known that I, FRANCIS MARION WISELEY, a citizen of the United States, residing at Los Angeles, in the county of Los Angeles and State of California, have invented a new and useful Pumping System, of which the following is a specification:

The primary object of this invention is to provide a system for pumping oil, water or other liquid from wells, rivers, lakes and the like, which shall be extremely simple and practical and which may be operated at a minimum expense.

Another object of the invention is to provide a pumping system in which there are no movable parts, essential to the operation of the system, below the level of the liquid.

A further object of the invention is to provide a pumping system which may be easily assembled and which will not become clogged by sand.

With these and other objects in view, as will become more apparent as the description proceeds, the invention consists in certain novel features of construction, combination and arrangement of parts as will be hereinafter fully described and illustrated.

Referring to the drawings, Figure 1 is a longitudinal, sectional view through the injector unit or foot piece of my pumping system. Fig. 2 is a detailed, longitudinal, sectional view through the collar or nozzle forming element of the system. Fig. 3 is a bottom plane view of Fig. 2. Fig. 4 is a longitudinal, sectional view through a slightly modified form of my device. Fig. 5 is a detailed, longitudinal, sectional view through the nozzle forming element or collar as illustrated in Fig. 4, and, Fig. 6 is a bottom plane view of Fig. 5.

Referring in detail to the drawings, by numerals, 1 designates a well casing having arranged concentrically therein a discharge pipe 2, which is connected at its lower end with a foot piece or injecting unit generally designated 3.

A feed pipe or tube 4, is arranged concentrically around the discharge pipe 2 and is connected by a threaded collar 5, to a cylindrical casing or barrel seat 6, formed with

an inverted conical bore or passage 7, having a ground wall. A collar 8, connects a nipple 9 to the lower end of the casing 6.

Within the casing 6, is positioned a barrel 10, of an inverted frusto-conical formation having its outer surface ground so as to form an air tight joint within the casing.

A head 11, is threaded into the upper end of the barrel and is formed with a conical interior 12, which communicates at its upper end with a constricted passage 13, formed through the throat 14.

The upper portion of the head 11 is conical as shown, and is encircled by a collar or nozzle-forming element 15, having a circular peripheral flange 16, at its upper end which is threaded into engagement with the lower end of the discharge pipe 2. This collar has a central conical shaped opening, the wall 17, of which is spaced a slight distance from the outer wall of the head 11 and held in this spaced relation by the internal lugs 18, formed on the collar 15, adjacent its lower end. The bottom edge of the collar is notched at intervals to form supporting lugs 19, which, by resting on the shoulder 20, of the head 11, assist in supporting the discharge pipe 2 and they space the collar 15 from the head 11 so as to form a continuous passage from the feed pipe to the discharge pipe. Set screws or pins 21, connect the collar 15 and the barrel head 11.

The barrel 10 has a port 22, formed in its lower end, said port being enlarged adjacent its upper end to receive a removable valve seat 23, having a central circumferential flange 24, which is engaged by the lower edge of a valve cage 25, which cage is threaded into the bottom of the barrel. A ball 26 operates within the cage to open and close the passage 22, leading into the interior of the barrel.

In operation gas is forced downwardly through the feed pipe 4 under pressure and as it flows through the restricted passage 26 into the discharge pipe 2, creates a suction upwardly which draws liquid through the nipple 9, port 22 and head 11 into the discharge pipe and then to the surface.

The discharge pipe 2 is of greater inside diameter than the outside diameter of the

throat 14 so as to form an annular space between the throat and discharge pipe of considerably greater cross sectional area than the cross sectional area of the restricted passage 26, thus utilizing expansive force of the gases to the utmost at the point of contact of the gases with the liquid being pumped through the throat and also thus allowing the column of liquid to spread 5 outward as is its wont so that the air will rise directly beneath the outwardly flaring portion of the liquid column and exert substantially direct upward pressure against said liquid. For some reason or reasons 10 which I am unable to fully explain, the fluid pump with this device issues from the well in a steady unbroken stream and the gases and liquid do not discharge alternately in 15 separate puffs such as occur with the use of prior devices.

Should the ball valve 25 or seat thereof become worn the entire barrel and discharge pipe 2 may be withdrawn from the well without disturbing the feed pipe or other 25 portions of the system and this feature I consider to be of primary importance from a practical standpoint.

On Sheet 2 I have shown a slightly modified form of my pumping system, which, 30 as is evident, is somewhat simpler in construction than the preferred form.

In Fig. 4 the barrel 27 is connected directly to the feed pipe 28 by a threaded collar 29 and to the nipple 30 by a threaded collar 31. This barrel has a cylindrical chamber 32 at its lower end and a conical chamber 33 at its upper end communicating with a restricted passage 34. The body or main portion of the barrel is cylindrical 35 whereas the upper end 35, is reduced to a conical shape. A nozzle forming member or collar 36 encircles in spaced relation, the conical portion 35, and is provided with a flange 37, which is threadingly engaged with 40 the discharge pipe 38. The lower end of the member 36 rests against the upwardly facing shoulder 39 of the barrel 27 and is notched as indicated at 40 to establish communication between the feed and discharge 45 pipes.

A plug 41 closes the lower end of the barrel 32, and is formed with a port or passage 42 surrounded at its upper end by an externally threaded flange 43 to which a valve cage 44 is connected. A valve seat 45 is housed within the cage and supports a ball valve 46. The valves 25 and 46 check any return flow of oil through passages 21 and 42 respectively and also prevent any gas 50 flowing through these passages, should a back pressure accumulate.

Although the construction of the modified form of my invention is simpler than that of the preferred form it cannot be so readily 55 repaired because the barrel cannot be with-

drawn from the well without removing also the feed pipe.

From the foregoing description taken in connection with the accompanying drawings, it will be evident that I have provided 70 a cheap, practical and highly efficient pumping system having very few movable parts and no intricate mechanism to become disarranged.

What I claim is:

1. In a pumping system, a barrel having a straight throat portion of less diameter than the diameter of the barrel below the throat, means to discharge gases upward around said throat, and a discharge pipe of greater inside diameter than the outside diameter of the throat surrounding said throat so as to form an annular space between the throat and discharge pipe. 75

2. In a pumping system, a barrel having a straight throat portion of less diameter than the diameter of the barrel below the throat, a collar surrounding and spaced apart from the barrel to form a restricted passage, means to discharge gases upward 80 through said restricted passage, and a discharge pipe of greater inside diameter than the outside diameter of the throat surrounding said throat so as to form an annular space between the throat and discharge pipe, 85

said annular space being of greater cross sectional area than the cross sectional area of said restricted passage. 90

3. In a pumping system, a barrel having a straight throat portion of less diameter than the diameter of the barrel below the throat and provided with an upwardly facing shoulder, a collar surrounding and spaced apart from the barrel to form a restricted passage and provided at its lower end with notches and having said lower end seated on said shoulder, a feed pipe discharging on to the shouldered portion, and a discharge pipe fastened to the upper end of the collar and surrounding said throat, said discharge pipe being of greater inside diameter than the outside diameter of the throat so as to form an annular space between the throat and discharge pipe and 100 said annular space being of greater cross sectional area than the cross sectional area of said restricted passage. 105

4. In a pumping system, a barrel having a straight throat portion of less diameter than the diameter of the barrel below the throat and provided with an upwardly facing shoulder, a collar surrounding and spaced apart from the barrel to form a restricted passage and provided at its lower end with notches and having said lower end freely 110 seated on said shoulder so as to be movable relative to the barrel, a feed pipe discharging on to the shouldered portion, and a discharge pipe fastened to the upper end of the collar and surrounding said throat, said 115

discharge pipe being of greater inside diameter than the outside diameter of the throat so as to form an annular space between the throat and discharge pipe and said annular space being of greater cross sectional area than the cross sectional area of said restricted passage.

In testimony whereof, I have hereunto set my hand at Los Angeles, California, this 26th day of August 1914.

FRANCIS MARION WISELEY.

In presence of—

RODNEY M. SMITH,

LORRAINE E. DURRAN.
